UNITED STATES PATENT OFFICE

2,446,342

SEWING MACHINE

Albert C. Peterson, Park Ridge, and Robert A. Hayes, Chicago, Ill., assignors to Union Special Machine Company, Chicago, Ill., a corporation of Illinois

Application June 28, 1946, Serial No. 680,146

7 Claims. (Cl. 112—203)

1

This invention relates to new and useful improvements in sewing machines and more particularly to a feeding mechanism for a machine adapted to stitch an inelastic lining strip or the like to an elastic body fabric such as, for example, knit underwear material.

In stitching such combinations of material, it is difficult to cause the elastic material to advance at the same rate as the inelastic material. If, for example, the elastic material is fed into the machine in a superposed relation to the inelastic material, the presser foot of the machine upon the top surface of the elastic material may retard or stretch this material, and similarly handling of the elastic material by the operator may cause this material to lag behind the inelastic material.

An object of the invention is to provide a simple machine of the above character having a feeding member which engages the elastic body fabric and feeds same to the stitching mechanism at the same rate as, or at a slightly faster rate than the inelastic strip is advanced by a feed dog. A feature of the present invention is that a blade-like top feeding member may be provided for feeding the elastic material from above.

An object of the invention is to provide a simple, single, rotary driving means for the blade-like top feeding member.

A further object is to provide a simple, single, accessible means for adjusting the length of the stroke of the blade-like member. A further object of the invention is to provide a driving mechanism for the blade-like top feeding member which is capable of positive simple lubrication.

A still further object is to provide a single rotary high speed driving means capable of causing the feeding edge of the top feeding member to engage the material with a roughly elliptical motion similar to that of a four-motion feeding means.

The above mentioned, as well as other objects, together with the many advantages obtainable by the practice of the present invention, will be readily comprehended by persons skilled in the art by reference to the following detailed description taken in connection with the annexed drawings which respectively describe and illustrate a preferred embodiment of the invention, and wherein

Fig. 1 is a front elevational view of a machine embodying in illustrative form this feeding arrangement, certain portions being broken away for clarity of illustration.

2

Fig. 2 is an end elevational view of the machine shown in Fig. 1, as seen from the left of that figure, partly in section.

Fig. 2—A is an enlarged diagrammatic view showing the path of travel of the lower edge of the feeding blade, as viewed in Fig. 2.

Fig. 3 is a top plan view of the base of the machine, partly in section, and with some parts omitted.

10 Fig. 4 is a fragmentary front elevational view of a portion of the sewing machine bed, illustrating the relationship of the needles and the lower folder which controls the inelastic lining strip.

15 Fig. 5 is a sectional view taken in the plane 5—5 as shown in Fig. 1, illustrating the gear arrangement.

Fig. 6 is a fragmentary elevational view of the lower feed lifting means, as seen from the end 20 of the machine shown in Fig. 2, certain parts being omitted for clarity of illustration.

Fig. 7 is a view partly in longitudinal section and partly in elevation of adjustable eccentric means for driving the top blade feeding means.

25 Fig. 8 is a plan view of the rotary shaft appearing to the right in Fig. 7, together with a portion of a stud driven eccentrically thereby.

Fig. 9 is an end view, partly in elevation and partly in section, of the components shown in 30 Fig. 8.

Reference is made to Fig. 1. The machine herein illustrated comprises a hollow base 10 and a hollow vertical column or standard 11 rising therefrom toward one end of said base and communicating therewith. Extending from and supported by said standard is a hollow arm 12 which overhangs said base, terminating at its free end in a hollow head 13. As shown in Fig. 2, mounted in the upper and lower walls of the head 13 are a pair of bushings 14 and 15, respectively, and journaled in these bushings for generally vertical reciprocation is a needle bar 16. As shown in Fig. 4, the needle bar 16 carries at its lower end suitable needle holding means 17, provided with a pair of needles 18.

Means are provided for reciprocating the needle bar 16. Mounted on this bar, as shown in Fig. 1, is a collar 19 held in place by a pair of screws 20 and provided with a lug 19a to which one end of a link 21 is pivotally attached. Mounted in the front and back walls of the arm 12 are a pair of bushings 22, and journaled for rocking therein is a shaft 23. Mounted on the shaft and adapted for rocking movement is a lever 24. This lever is provided at its lefthand

end with a generally longitudinal slot 25 and has a pair of jaws, not shown, at the outer end of said slot. These jaws are clamped by suitable means to a pin extending from and pivotally mounted in the link 21.

The right-hand end of the lever 24 is provided with a ball stud 28 and a pin 29 projecting therefrom. These members may, for convenience in assembly, be part of a separate, attachable portion of the lever 24. The lever 24 is driven by a pitman 30 having attached to its upper end a split, socket-like strap 31 which cooperates with the ball stud, provided with a forked extension 32 which cooperates with the pin 29.

Journalled in the base 10 is a crank shaft 33 provided with a crank 34. Attached to the lower end of the pitman 30 is a socket-like split strap 35 adapted to engage a ball-like portion of the crank 34. Mounted on the shaft 33 toward its right-hand end outside the base is a hand wheel and belt pulley 36 for driving said shaft. This pulley may be driven by a belt from a conventional transmitter unit, not shown. When the shaft 33 is caused to rotate, it in cooperation with the crank 34, the pitman 30, the lever 24, the link 21, and the needle bar 16, causes the needles 18 to be reciprocated vertically.

As shown in Fig. 2, mounted in the upper and lower walls of the head 13 are a pair of bushings 37 and 38, respectively, and guided for vertical movement in these bushings is a presser bar 39, to the lower end of which a presser foot 40 is attached as by a suitable clamping collar 41.

Yielding means are provided for urging the presser bar downward. As shown in Fig. 1, threaded into the top wall of the arm 12 is a screw 42 held in place by a lock nut 43. The apparatus includes a bowed, horizontal leaf spring 44 provided with a lengthwise slot so that it may be fitted over the screw 42. The bar 39 is provided at its upper end with a shoulder 45 and a pin-like portion 46 of reduced diameter. The left-hand end of the spring 44 is provided with a forked portion 47, as shown in Fig. 2, which straddles the pin-like portion 46 of the bar 39. The right-hand end of the spring 44 rests on and is retained by a portion of the standard 11 which is not shown. The spring 44 is pressed downward in the region of the screw 42 by a smaller auxiliary leaf spring 48, which is held in place and which may be positioned by a thumb nut 49. In this manner the spring 44 exerts a downward pressure on the shoulder 45 of the bar 39, the pressure being adjustable by means of the nut 49.

Means are provided for lifting the presser foot. Pivotally mounted in the rear wall of the arm 12 is a rockable shaft 50. Connected to this shaft and extending therefrom is an arm 51. Mounted on the presser bar 39 is a collar 52. The rear wall of the head 13 is provided with a slot, not shown, and the collar 52 has an arm 52a extending rearwardly through said slot. One end of a link 53 is pivotally connected to the free end of the arm 51, and the other end of said link is pivotally connected to the free end of the arm 52a. The frame is provided with a projection 54, and a spring 55 is connected between this projection and the free end of the arm 51 so as to retain this arm in satisfactory operating position.

Also extending from the shaft 50 is an arm or lever 56. This arm is provided at the end opposite the shaft 50 with an opening 57 for at-

achment of a chain from some controlling means, such as a treadle, not shown. When the arm 56 is pulled downward, the presser foot will be lifted by linkages described.

Means not completely shown are provided for decreasing the thread tension when the presser foot is lifted. For controlling such means, a shaft 58 is journalled in the walls of the standard 11, and extending radially therefrom is a lever 59. A link 60 is pivotally connected to the lever 59 and to the arm 56 so that the shaft 58 is actuated whenever the arm 56 is actuated. The rocking of the shaft 58 decreases the thread tension by means not shown. For further details of such tension releasing means, reference may be made to U. S. Patent No. 1,823,817, granted to Norman V. Christensen on Sept. 15, 1931.

The base 10 is provided with various plates, including a supporting plate 61, a cloth plate 62 and a throat plate 63. As shown in Figs. 1, 2 and 3, the presser foot 40 is by the action of the spring 44 pressed toward the throat plate, and the forward end of the foot is upwardly inclined for reception of the material being sewed.

A slideable plate 64 is mounted in the cloth plate 62. Mounted on the slideable plate 64 is a support 64a, on which is mounted an upper folder 65, for guiding the elastic material.

The base 10 and the lower part of the standard 11 are adapted for serving as an oil reservoir, and oil is provided therein. Mounted on the shaft 33 within the base is a gear 66, and adjacent said gear is an oil distributing disc 67 having a hub portion 68 attached to the shaft. As shown in Fig. 3, mounted on the shaft beyond this point is an eccentric 69, having a strap 70 cooperating therewith.

Journalled in the front and back walls of the base 10 is a shaft 71, shown in Fig. 1, which is, by conventional means not shown, driven with a rocking motion by the strap 70. Mounted on this shaft is an arm 72 having an end pivotally attached to one end of a rod 73. The machine is provided with a pair of loopers 74 appropriately mounted and adapted to be oscillated by the motion of the rod 73 in response to the rotation of the shaft 33. For more complete details of typical means for actuating the loopers, reference may be made to U. S. Patents No. 2,011,491 granted to Frank A. Kucera on August 13, 1935, and No. 1,699,262 granted Jan. 15, 1929, to August J. Wohlpart.

The machine is provided with a lower feeding means for advancing the inelastic lining strip, including a feed dog 75 and means for driving same with a four-motion counterclockwise movement as viewed in Fig. 2. The base 10 is provided with upward extensions 10a, and journalled for rocking in these extensions is a shaft 76. Mounted on this shaft and extending upwardly therefrom is a feed rocker 77, toward the upper end of which is pivotally mounted a feed bar 78. The feed dog 75 is carried by the feed bar at its free end, being affixed thereto by suitable means.

Rigidly attached to an extension of the feed rocker is one end of a lever 79, the other end being pivotally attached to one end of a strap-like lever 80. Eccentric means, generally indicated by the numeral 80a, are provided for imparting an eccentric motion to the strap-like lever 80. Such eccentric means are mounted upon a shaft 33a, coupled to and axially aligned with the shaft 33. Means may be provided for varying the eccentricity of the eccentric means 80a, if desired.

It will be noted that rotation of the shaft 33a will cause a back-and-forth movement of the feed dog by the cooperation of the linkages described. Separate means are provided for imparting an up-and-down motion to the feed dog. Mounted on the shaft 33a, as shown in Fig. 6, is an eccentric 81, and cooperating with this eccentric is a strap 82. The feed bar 78 is provided with an integral extension 78a, to which the strap 82 is pivotally attached. Rotation of the shaft 33a produces an up-and-down motion of the feed dog, which, in combination with the previously described motion, provides the four-motion movement desired. The direction of rotation of the shafts 33 and 33a, as viewed from the end of the machine shown in Figs. 2 and 6, is clockwise, and the direction of movement of the feed dog 75 as shown in these figures is counterclockwise. For further details of somewhat similar means for driving a feed dog, reference may be made to United States Patent 1,817,727 granted August 4, 1931, to August J. Wohlpert.

Attention is now directed more particularly to the top blade feeding mechanism. The base is provided with a flat plate 63, as shown in Fig. 1, and rising from this plate is a generally vertical hollow standard 84 having a generally horizontal hollow arm 85. The arm 85 is provided with journalled supports 86 and 87, and mounted in said supports and extending horizontally through the arm 85 is a rotary shaft 88. Mounted on the shaft 88 is a gear 89 as shown in Figs. 1 and 5. Journalled in the standard 84 is a stub shaft 90, and mounted on this shaft is an idler gear 91, cooperating with the gear 89 and with the gear 66. The previously mentioned oil distributing disc 67 dips into the oil held in the base and when the shaft 33 is rotated, this disc distributes oil upwardly to the gears 66, 91 and 89.

Reference is made to Figs. 1, 2 and 7-9. Means are provided for deriving an eccentric motion from the rotation of the shaft 88. Adjustably affixed to a portion 88a of the left-hand end of this shaft is a crank stud 92, the axis of the stud being eccentrically positioned with respect to the axis of the shaft 88. For engaging the stud 92, the portion 88a of the shaft 88 may be provided at its left end with a generally diametrical slot of T-shaped cross-section, the stud 92 having a portion 92a adapted to be engaged therein. The stud 92 carries a sleeve 93, and is threaded at its free end to receive a nut 94. When this nut is loosened, the eccentricity of the stud 92 and the sleeve 93 with respect to the axis of the shaft 88 may be adjusted by a screw 95 which is threaded into the portion 92a of the stud 92 and has a circumferential slot 95a engaging an arcuate collar-like member 96 attached to the portion 88a of the shaft 88 by a pair of screws 97. When the screw 95 is turned, the stud 92 is shifted radially with respect to the shaft 88. Between the nut 94 and the sleeve 93 is a washer 98. When the nut 94 is tightened, the stud 92 and the sleeve 93 are secured in adjusted position with respect to the shaft 88 since the sleeve is forced by the nut and washer toward the right on the stud 92 so as to press against the end of the portion 88a of the shaft 88.

As shown in Fig. 2, pivotally attached to a portion of the head 13 is one end of a link 99. There is provided a feed rocker or movable support 100 having a sleeve-like portion 100a with internal anti-friction needle bearings 101, shown in Fig. 7, pivotally mounted on the sleeve 93. The rocker 100 also has an upstanding arm piv-

otally attached at a point 102 to the other end of the link 99, and a horizontal arm to which a plate 103 is pivotally attached at a point 104. A blade 105 is attached to the plate 103 by screws 106. The blade 105 and the plate 103 may together be called a feeder or feeding member. Slots in the blade 105 are provided at the screws 106 for adjustment of the position of the blade. The rocker or movable support 100 is provided with an integral lug portion 100b to which a spring 107 is attached by an adjustable stop screw 108 and a nut 109. The spring 107 tends to urge the blade 105 to rock in a counterclockwise direction about the point 104, as seen in Fig. 2, and the screw 108 limits the extent to which it may so rock. The machine is provided with a lower folder 110 for guiding the inelastic lining tape, supported by a bracket 111 attached to the base 10. As a part of the work guiding means, a spring separator blade 112 is provided, mounted on the previously mentioned support 64a. The blade 105 extends toward this separator blade 112 and has a serrated lower edge for engaging the elastic material on the upper surface of the separator blade.

The rotation of the shaft 33 in a clockwise direction as viewed from the end of the machine shown in Fig. 2 will, through the gears 66, 91 and 89, drive the shaft 88 also in a clockwise direction. When the shaft 88 is rotated, the stud 92 and sleeve 93 will rotate eccentrically within the bearings 101 of the sleeve-like portion 100a of the rocker 100. Since in the present embodiment the link 99 limits to a circular arc the possible position of the point 102 of the rocker, the eccentric driving action of the stud 92 and sleeve 93 on the rocker causes the point 104 to move in a roughly elliptical, clockwise path.

At certain points in the cycle the lower edge 40 of the blade 105 is raised, and at other points it is lowered. When the blade is lowered to such an extent that its bottom edge is pressed against the material on the separator blade 112, the tendency of the blade 105 to rock about the point 104 in response to the force from the spring 107 is no longer limited by the stop screw 108, but is limited by the separator blade 112 and the material thereon. At certain points of the cycle, however, when the blade 105 is raised, the stop screw 108 limits its rocking about the pivot point 104. As a result, the lower edge of the blade 105 moves in a generally clockwise path which is roughly elliptical, but somewhat flattened on the bottom, as illustrated in Fig. 2-A. The motion of 55 the lower edge of the blade 105 is similar to what is usually termed a four-motion movement; that is, there is a back-and-forth movement and also an up-and-down movement. In the present case, since feeding is done from above, the forward or feeding stroke is in the lower portion of the path, while the recovery stroke is in the upper portion of the cycle. During the major portion of the feeding stroke the lower edge of 60 the blade 105 is caused to move parallel to the separator blade 112 as the work slides along this blade. It is during this time that the blade 112 and the material thereon serve to limit the pivoting of the blade 105 about the point 104. As a result of the above-described motion of the blade 105, the elastic material is fed in a succession of strokes toward the stitching mechanism. It is observed that this four-motion feeding action is derived from a single rotary actuator or eccentric, as distinguished from the usual type of four-

motion feeding means, which employs two eccentrics.

The previously described means for adjusting the eccentricity of the stud 92 provides means for adjusting the length of the feeding stroke of the blade 105. The machine can thus be adjusted so that the elastic material is fed at least as rapidly as is the inelastic material.

It is to be understood that instead of using a link such as 99 to limit the possible position of the point 102, other means could be employed. Thus a frame member could be provided with a curved slot, and the rocker 100 could be provided with a block portion at the point 102 adapted to operate in said slot. The shape of the slot would then limit the motion of the point 102 to a predetermined path, which need not necessarily be an arc of a circle. Similarly the rocker or movable support 100 for the feeder could be driven in a predetermined path by means other than the eccentric means described.

Provision is made for positive, simple lubrication of the driving mechanism for the top feeding member 105. As shown in Fig. 7, the sleeve-like portion 100a of the rocker or movable support 100 is provided with an opening 113 through which oil may be supplied manually for lubricating this driving mechanism.

As shown in various figures, the entire machine is provided with a lubrication system including a number of oil conduits 114. It is also provided with various conventional elements such as thread-guiding means, generally indicated by the numeral 115.

While an illustrative form of the invention has been disclosed in considerable detail, it will be understood that various changes may be made in the construction and arrangement of the several parts without departing from the general principles and scope of the invention as defined by the appended claims.

We claim:

1. In a sewing machine having a stitching mechanism, a feeding mechanism comprising an eccentric means, a movable support adapted to engage said eccentric means and to be driven bodily thereby, means engaging said support at a point and enabling limited movement of said point but confining said movement to a predetermined path, a feeding member pivotally connected to said support for engaging and advancing the work toward said stitching mechanism, means urging said feeding member to rock about its pivot in such a direction that a portion thereof is pressed toward the work, stop means for limiting the rocking of said member, and means for actuating said eccentric means.

2. In a sewing machine having a frame, a stitching mechanism and a work surface, a feeding mechanism comprising a rotary eccentric means, a movable support adapted to engage said eccentric means and to be driven thereby, a feeder pivotally mounted on said support for engaging and advancing the work on said work surface in advance of the stitching mechanism, a member pivotally connected to said frame and pivotally connected to said support, means urging said feeder to rock about its pivot in such a direction that a portion thereof is pressed toward the work on said work surface, and stop means for limiting the rocking of said feeder in said direction.

3. In a sewing machine having a frame, a stitching mechanism and a work surface, a feeding mechanism comprising a rotary eccentric

means, a movable support connected to said eccentric means and adapted to be driven thereby, means confining a point of said support to a circular arc, a feeder pivotally connected to said support, having a generally blade-like portion extending slantingly toward said work surface in advance of said stitching mechanism, a spring for urging said feeder to rock about its pivot in such a direction that said blade-like portion is urged toward said work surface, and stop means other than said work surface for limiting the extent of rocking of said feeder in said direction during most of the recovery part of the cycle, the extent of said rocking during most of the feeding part of the cycle being limited by engagement of said blade-like portion with the work on said work surface.

4. In a machine for sewing a relatively inelastic material to a relatively elastic material, 20 said machine having a frame, a work surface, a stitching mechanism and means for feeding said inelastic material, apparatus for feeding said elastic material at least as fast as said inelastic material is fed, comprising rotatable eccentric 25 means, a bell crank lever mounted on said eccentric means generally at the junction of the arms of said lever and adapted to be driven by said eccentric, a link pivotally connected to one arm of said bell crank lever and pivotally connected to a part of said frame, a blade-like feeding member pivotally supported on the other arm of said bell crank lever and having a portion extending generally toward said work surface in a direction convergent with same toward 30 said stitching mechanism, yielding means urging said feeding member to rock with respect to said bell crank lever in a direction toward said work surface but away from said stitching mechanism, stop means connected to said bell crank 35 lever adapted to limit the extent of rocking of said feeding member in said direction, and means for rotating said eccentric means so that a portion of said feeding member in the region of said work surface describes a four-motion 40 feeding movement.

5. In a sewing machine, apparatus for imparting a four-motion movement to a member, comprising an eccentric means, a movable support to which said member is pivotally connected, 50 said support being connected to said eccentric means and adapted to be driven thereby, means for limiting the motion of a point on said support to a predetermined arcuate path, means urging said member to rock on its pivot, and 55 means for limiting to different extents at different times in the cycle the rocking of said member.

6. In a sewing machine having a feeding member, apparatus for imparting with a single rotary actuator a four-motion movement to said feeding member, said apparatus comprising a rotary actuator, a movable support connected to said rotary actuator and adapted to be driven thereby, means for limiting the motion of a point on said support to a predetermined arcuate path, 60 said feeding member being pivotally connected to said support, spring means for urging said feeding member to rock on its pivot, a stop connected to said support adapted to engage said feeding member and limit the extent of its rocking during a portion of its cycle of movement, and means having a generally plane part adapted to limit the extent of rocking of said member 65 but to enable a part of said feeding member to

move generally parallel to said plane part during another portion of said cycle.

7. In a sewing machine having a frame, a stitching mechanism and a work surface, a feeding mechanism comprising a feeding member for engaging and advancing the work on the work surface in advance of said stitching mechanism, a movable support to which said feeding member is pivotally connected at a first point, means for limiting the possible position of a second point of said support to an arcuate path, a spring urging said feeding member to rock about its pivot in such a direction that a portion thereof is pressed toward the work on said work surface, stop means for limiting the rocking of said feeding member in said direction, eccentric means for moving said support, said last-mentioned means comprising a rotary shaft, a stud adapted for attachment to the end of said shaft in a gen-

erally parallel eccentric relationship thereto, the degree of eccentricity being adjustable by radial positioning of said stud, means for securing said shaft in adjusted position, said movable support being provided with internal antifriction bearings and being pivotally mounted on said stud at these bearings, and means for driving said rotary shaft.

ALBERT C. PETERSON.
